UNITED STATES PATENT OFFICE.

SWITS CONDÉ, OF OSWEGO, NEW YORK.

DESIGN FOR A KNIT SHIRT.

Specification forming part of Design No. **11,443**, dated September 30, 1879; application filed August 5, 1879.
[Term of patent 7 years.]

To all whom it may concern:

Be it known that I, SWITS CONDÉ, of Oswego, in the county of Oswego, in the State of New York, have invented a new and useful Design for Knitted Shirts, of which the following, taken in connection with the accompanying drawing, is a full, clear, and exact description.

The accompanying drawing represents the body of a knitted shirt, in which *a* and *a'* denote plain and mottled stripes, respectively, the mottled stripe being composed partly of the color of the plain stripe. These stripes are perfectly straight and parallel to each other, and arranged vertically on the garment.

I am aware that it is common to make prison-suits with plain stripes arranged horizontal or

transverse on the garment; hence I do not claim such a design.

What I do claim as my invention is—

The design for a knit shirt, consisting of straight mottled and plain stripes arranged alternately parallel to each other and vertically in relation to the garment, substantially as described, and shown in the accompanying illustration.

In testimony whereof I have signed my name and affixed my seal, in the presence of two attesting witnesses, at Oswego, in the county of Oswego and State of New York, this 25th day of July, 1879.

SWITS CONDÉ. [L. S.]

Witnesses:

FRED L. CONDÉ,
EDW. MAXWELL.
